DENTAL ARTICULATOR

Harold J. Thompson, Minneapolis, Minn.

Application August 25, 1952, Serial No. 306,114

6 Claims. (Cl. 32—32)

1

This invention relates to dental articulators and to the making of dentures by means of an articulator, which dentures will have an improved construction that will more nearly simulate functionally the naturally formed teeth in the human mouth.

I have approached the problem of proper articulation in the construction of dentures by first considering the mal-function of teeth in their natural state, then assuming that corrective measures, either natural or artificial, which will solve problems arising from the occlusal topography of human teeth will also solve the same problems arising from the same defects in the occlusal topography of the teeth in the case of dentures. Mechanical forces of mastication normally directed will be distributed by the supporting tissue structures. If these mechanical forces are abnormally directed, there will be a reaction of the supporting tissues resulting in local stresses or loads in excess of that which the tissue structure is capable of withstanding. These local and concentrated forces first cause an irritation and subsequently a traumatic condition which ultimately may become irreparable. A large number of cases of pyorrhea are directly attributable to this cause alone. The reason for the traumatic condition results from a localization of high stresses caused by the strength muscles of the jaw being concentrated in a much smaller area than nature intended. Since the natural building bulk in the tissues of the gums is no greater than necessary for distributed forces, an unusually greater concentration of force will cause a breakdown of the supporting tissues at the particular region of force. As a premise therefore in developing an articulator which will aid in the construction of dentures which give balanced occlusion for comfort and efficient mastication I have discovered that the same forces that operate to promote long healthy function of the natural dentition in their ordinary situation also are required to stabilize and promote retention potential in artificial dentures. In order to reproduce dentures which will evenly distribute stresses between the upper and lower teeth thereof it is necessary that they not only fit in centric relation during immobile occlusion but will also evenly distribute the stresses during all of the normal movements produced by the mandible during the biting and chewing of food.

In the case of natural dentition, cusps out of alignment can cause disharmonious function in specific areas of the mouth which, if not corrected, will result in trauma of the gum tissue

which are abnormally stressed thereby. Improper corrective measures, although correcting the specific fault at one point, can result in progressive failure of a number of teeth and surrounding tissue. Similarly in prosthetic dentition cusps out of alignment can cause a force which is transmitted by the dental plate to the gum tissue and cause local irritation at the point of stress. Unfortunately, the point of irritation more often than not fails to point up the source of cusp misalignment. The patient is thus led to believe that his dental plate has a high spot or pinching quality in a gum area remote from the origin of the stress. When the dentist yields to the patient's wishes and grinds away the imaginary high spot the misalignment is not in any way corrected but the stress is shifted to a new area with the original irritated area now being out of intimate contact and failing to contribute towards retention of the plate. Furthermore, miscorrection merely intensifies the lack of retention without correcting the basic trouble.

It is therefore a general object of the invention to provide a dental articulator which will simply and positively indicate the precise facet construction of both the anterior and the posterior teeth necessary to produce a matching set of upper and lower dentures which will not only fit in centric relation but will operate functionally during mastication without creating pressure on particular local areas of the gums.

In order to so determine the correct faceting of the teeth during the construction of dentures by a physiodontist (commonly called a laboratory set-up technician) it becomes necessary to understand the various movements of the human jaw. There have been many treatises on the structure and movement of the human mandible which have more or less crystallized into a theory called the condylar inclination theory, stating in substance that the frictional movements of the jaws during mastication are guided by surface formation of the temporo-mandibular joint itself. However, in the case of articulators which have been constructed according to the condylar inclination theory the calculated mechanical co-action of the condyle in contact with the glenoid fossa does not result in an instrument which can predict the proper faceting of the individual tooth cusps during the actual construction of the dental plates.

I have developed a new theory of articular occlusion which I call the functional facet theory and which states in substance that the movements of the jaw are guided by automatically

controlled bi-lateral sets of muscles acting on a compound-complex lever of the third class. The muscle action upon each bi-lateral joint may be in unison with the other, in opposition therewith, or in multiple combinations of actions upon the mandible as a whole, the condyle of which functions as a facultative fulcrum with the pull of the muscles being the determining guidance. With this in evidence it is possible to arrive at a definition of true centric relationship, namely the center of muscle pull when the mandible is in its most retruded position in relation to the glenoid fossa. This is important since an exact starting point can be obtained and transferred from the mouth to the articulator by means of trial plates and wax check blocks. This furnishes an exact and correct starting point for each movement away from centric, always under controlled guidance. I have performed numerous experiments to arrive empirically at the pattern of movement between the teeth of the mandible or lower jaw relative to the teeth of the upper jaw. These experiments were performed by taking plaster casts from normal dentulous human mouths and mounting them in free suspension from three points, then imitating the natural movements of the jaw during mastication while at the same time recording and preserving in clay pantographic tracings in the attempt to arrive at a standard and uniform action which could be used in the construction of an articulator. From these experiments I discovered that the tracings obtained were surprisingly uniform regardless of the size or shape or combination of shapes of the dental arches. The articulator which I have developed in the light of these experiments simulates lateral shifting of the mandible relative to the upper jaw as well as forward and backward movement, either simultaneously or consecutively to obtain a variety of combinative movements. Dentures made with the use of my articulator allow intricate movements of the user's jaw which result in an unusually high degree of satisfaction. Dental plates, which have previously given trouble, when corrected in my articulator are invariably completely satisfactory since the correction is made at the occlusal surfaces of the plates and not at the point of irritation upon the patient's gum. Plates constructed under my method utilize teeth having cusps of average height, no advantage being noted in the use of deep grooves and high cusps on the one hand or in flat teeth on the other hand. In other words the dentures constructed by my method conform as closely as possible to the natural facet inclinations and disposition of the teeth as is possible. It is consequently a further object of the invention to provide a device for determining the correct facet function in the preparation and correcting of dentures which will employ a three-point suspension with a definite guided differential action simulating throughout the normal use thereof the complex relative movements between human jaws with teeth having facets worn naturally therein.

It is a still further object of the invention to provide for an articulator responding simply and efficiently to contoured guiding or bearing surfaces between the relatively movable upper and lower portions thereof, the formation of the contoured surfaces being simply selected according to the general pattern of movement between the occlusal surfaces of the normal dentulous mandible with relation to the dentulous maxilla with

the articulator pre-set in spaced relation even before beginning the setting and grinding of the individual artificial teeth.

These and other objects and advantages of this invention will more fully appear from the following description made in connection with the accompanying drawings wherein like reference characters refer to the same or similar parts throughout the several views, and in which:

Fig. 1 is a side elevation of my articulator showing partly completed dentures mounted therein in dotted line representation;

Fig. 2 is a front elevation of my articulator;

Fig. 3 is a top elevation of the articulator;

Fig. 4 is a diagrammatic representation of the suspension means showing the relative positions between the bearing pins and the concave surfaces of the sockets when the upper structure is moved directly backwards with respect to the base structure; and

Fig. 5 is a diagrammatic representation similar to that of Fig. 4 showing the relative positions of the bearing pins and the concave surfaces of the socket members when the upper structure is moved differentially over the socket surfaces.

Referring now to the drawings, my articulator comprises a rigid base structure R for supporting the entire mechanism. The structure R comprises a base or lower platform 10 to which may be secured a cast mount 11 which will position and retain plaster casting material upon the base 10. At the rear of the base 10, is an up-standing portion 12 which in turn comprises a pair of vertical parallel standards 13 and a cross bar 14 slidably mounted upon the standards 13 and adjustable therewith by thumb nuts 15. The cross bar in turn has an extending gooseneck 16 which terminates at its upper portion in a sleeve 17. Slidably mounted within the sleeve 17 is a resilient hold-down member 18. A centrally bored bolt 19 serves as a guide for the rod 20 which is secured at its lower end to the hold-down member 18. A compression spring 21 is mounted between the hold-down 18 and the sleeve member 17 so as to constantly urge it in a downward direction. A stop nut 22 is threadably disposed at the upper end of rod 20 so as to limit the downward movement of the hold-down member 18. In normal usage the hold-down 18 bears upon a cam surface 23 at the rear of the movable upper structure designated generally by the letter M.

The movable upper structure M in turn comprises an upper platform 24. A laterally extending arm 25 is secured integrally therewith to form a generally T-shaped platform. The lateral arm 25 has at each side an abutment or knob 26 and 27 which may be utilized manually for manipulating the articulator. Removably secured to the platform 24 is an upper cast mount 28 which may have a threaded upstanding portion extending through the platform 24 and secured as at 29 by a cooperating threaded element.

The movable upper structure M is connected with the rigid base structure R through a three-point suspension means S. For the sake of convenience, I prefer to use a pin and socket arrangement as shown. The suspension means S is symmetrically positioned with respect to both the base structure and upper structure in its centric relationship. In particular, the suspension means S comprises a left socket bearing 30 which is secured to the cross bar 14 as by screws 31. A right socket bearing 32 is similarly posi-

tioned and secured to the cross bar 44 by screws 31. Secured forwardly and at a lower position is the socket bearing 33. The left and right rear bearings 30 and 32 have similar contoured surfaces 34 and 35 respectively. The forward socket bearing 33 has a contoured surface 36 which varies somewhat from that of the rear socket bearings as will be more fully described hereinafter. The portion of the suspension means S which is attached to the movable upper structure M comprises a pair of bearing pins mounted upon the lateral arm 25, the bearing pin 37 being mounted at the left-hand side as viewed in Fig. 2 and the bearing pin 38 being mounted at the right-hand side. These pins 37 and 38 may be integrally formed with the lateral arm 25 of the upper platform or may be removably attached thereto by threaded connection and retained by such means as nuts 39. A forward bearing pin 40 is adjustably secured in upstanding relation to the horizontal structure M through an opening in forward sleeve portion 41. It is understood, of course, that when the movable structure M is moved from its horizontal position, the bearing pin 40 will retain its relative position with respect to the upper structure M. Communicating with the sleeve 41 for securing the adjustable and elongated bearing pin 40, is a thumb nut 42. When the upper structure M is in horizontal or parallel relation with the base 10, the bearing pins 37, 38 and 40 should all contact the contoured surfaces 34, 35 and 36 at their lowermost central position. In order to emphasize the correct parallel positioning, a small central guide depression 43 is formed at the bottom of each of the contoured surfaces and is shown in detail in the diagrammatic representations of Fig. 4 and Fig. 5.

In the use and operation of my articulator conventional steps are followed to a large degree. Briefly summarizing these steps, an impression is first made in modeling compound of the patient's mouth following which a plaster cast is poured in the modeled form. Next, a shellac compound is formed over the plaster case with the fingers to form a base plate tray. A plastic material such as a hydrocolloid is then placed in the tray and it is then inserted back into the patient's mouth in order to obtain finer detail. The hydrocolloid, which I prefer, is alginate cream. When the alginate has set, a final cast is poured into the base plate tray, the casting material used being a hard, stone-like plaster. The bite tray is then formed from the shellac compound by adapting to the final cast with finger manipulation and after warming the shellac. Base plate wax is then softened and adapted to each bite tray at the outer surface thereof. The upper and lower bite trays, together with the soft wax, is then put in the patient's mouth and he is instructed to close his jaws to obtain a normal position of the mandible with respect to the maxilla. A register mark is then made between the masses of wax secured to the upper and lower bit trays and the wax is then quickly chilled with water so as to retain its position in a hardened state and the trays are then removed from the patient's mouth. It is understood of course that in the event that only an upper or lower plate is being made, that a cast of the opposed natural teeth must be made in order to properly articulate the artificial plate according to my theory of occlusal faceting. I then pour plaster in a mass 44 upon the lower

cast mount 16 and the upper and lower bite plates are positioned in the wet plaster in registered position. The alveolar ridge of the upper bite plate is then positioned centrally and horizontally in the plaster, visual alignment usually being sufficient since the ridge does not form a true plane which is subject to measurement. After the plaster sets, at 44, another mass of plaster 45 is molded around the upper cast mount 16 and within the upper bite plate. At this point, the articulator is checked to see what the upper movable structure is parallel with the lower supporting structure. The elongated bearing pin 40 may be slidably adjusted until all the bearing pins 37, 38 and 40 lie in the central depressions 43. The bite plates are next removed and the bite wax is then taken from the bite plate. The bite plates are returned to the final casts preparatory to fixing the artificial teeth thereto. The wax is sparingly spread on the forward part of the upper bite plate and six upper anteriors are then positioned in the wax so as to conform to the natural appearance requisite for pleasing the patient. It is understood, of course, that some technicians may prefer to work with a lesser initial number of anteriors such as, for example, two or four. Next, I place the matching lower six anteriors upon the lower bite plate similarly secured with wax. The articulator is then used to get the proper facet movement between the upper and lower anteriors secured at this time to the bite plates. The technician may place his thumbs upon the knobs or abutments 26 and 27 causing the entire upper movable structure to move in an infinite number of differential positions. It is to be noted that all movement is backwardly from centric. This movement, of course, responds to the forward movement of the mandible from centric position in the human mouth since, for convenience, the upper plate is relatively moved with respect to the fixed lower plate, the above backward movement from centric is equivalent to the natural forward movement from centric in the case of the human mouth. Referring now to Fig. 4, this movement is diagrammatically set forth so as to illustrate the three-point suspension as well as the complexity of movements which occur when the abutment members 26 and 27 are simultaneously and individually moved backward from their centric position. Thus, when the entire movable upper structure is given a straight backward push, the bearing pins 37 and 38 will climb slightly upon the contoured surfaces 34 and 35 of the rear bearings 30 and 32. The front bearing pin 40 will similarly climb upon the contoured surface 36 of the socket bearing 33. Since, however, the rate of curvature of the contoured surface 36 is less than that of contoured surfaces 34 and 35, the upper movable structure, diagrammatically indicated by the letter M, will climb slightly higher at the rear, or the left, as viewed in Fig. 4, than the front portion adjacent the bearing pin 40. Now, however, if the rear bearing pins 37 and 38 are caused to advance unevenly in their rearward movement from centric position, a result typified diagrammatically in Fig. 5 may result. It may be seen that bearing pin 37 has been pushed rearwardly to a greater degree than bearing pin 38. This will cause the bearing pin 37 to raise the left rear portion of the movable upper structure when looking at the articulator as in Fig. 2 to a greater degree than the right rear

portion. Since the front bearing pin 40 has moved but a short distance from centric and on a surface having a lower rate of curvature, the front portion of the movable upper structure will have raised to an even lesser degree. Although the foregoing description of the manipulation of the articulator has been made with reference to the twelve opposed anterior teeth, the same procedure is employed throughout the entire operation. The individual teeth are ground so as to acquire facet surfaces which will be in contacting relationship throughout the complex differential movements given to the articulator as above described. The posterior teeth are next placed upon the bite plates in a similar manner and facet surfaces are ground thereon to conform to the same movements which were given the upper structure in articulating the anterior teeth.

In my experimental work, to determine the proper points of suspension and rates of curvature in the socket bearings, I was surprised to discover that the movements of the mandible in a human dentulous mouth with respect to the maxilla was very nearly exactly repetitious for all types, shapes and sizes of jaws. The measurements which I found to give me the best results were a thirteen-sixteenths of an inch radius for the curvature of the surfaces of the rear socket bearings and one and one-half inches radius for the contoured surface of the forward socket bearing 33. Although a spherical surface segment was found to be the best form for practical reasons in the manufacture of the articulator, it is understood, of course, that only the rear halves of all the socket bearings are actually employed during articulation. Since the rate of curvature of the socket bearings is variable with the distance between them, I found that the central depression points 43 of the rear socket bearings should be one and seven-sixteenths inches on each side of the center line. Also, the relative position of the front socket bearing was found to be four and five-eights inches from the front pin to the line connecting the rear bearing pins. Since it is the differential and complex movement of the upper structure with respect to the base structure that determines the success of my articulator, any variations of the dimensions which I have given that will produce the same movements would be acceptable in building an equivalent articulator. It is to be noted, however, that I have selected my dimensions on the basis of conservation of structural material on the one hand as opposed to freedom of operation and balanced design on the other hand.

It may thus be seen that I have devised a new and useful articulator, the function of which is based on the almost unanimous similarity of movements between the upper and lower jaws of the normal human dentulous mouth at the occlusal or faceted tooth surfaces. My articulator has thus been simply developed from the end result rather than attempting to devise an articulator, on the other hand, which would reproduce all the complex movements of the jaws under the condylar theory which, with respect to articulation, disregards the effect of ultimate faceting acquired by normal teeth during the use and wear thereof. It is to be further noted that all my faceting of artificial teeth is accomplished while maintaining the upper structure in positive, three-point suspension with relation to the base structure, the two structures being relatively movable laterally as well as longitudinally on

contoured surfaces. As a result there will be no latitude or guess work in selecting the proper occlusal pattern throughout the articulation of artificial teeth when using my articulator.

5 It will, of course, be understood that the movable upper structure may be fixed while the fixed base structure is caused to be relatively movable and that various other changes may be made in the form, details, arrangement and proportions 10 of the parts without departing from the scope of my invention which, generally stated, consists in the matter shown and described herein and set forth in the appended claims.

What I claim is:

1. In a dental articulator a supporting structure having a base with a lower cast mount thereon for securing rigidly thereto the cast of a lower jaw, a movable upper structure normally parallel to said base and having an upper cast mount 20 thereon for securing rigidly thereto the cast of an upper jaw, and a three-point suspension between the movable upper structure and the supporting structure comprising two spaced rear suspension members, each having a sliding connection 25 including a bearing member on the upper structure with a concave bearing surface in the supporting structure, and a front suspension member having a sliding connection including a bearing member mounted on the upper structure 30 and a concave bearing surface in the supporting structure said two rear concave surfaces having a greater rate of curvature than that of the front concave bearing surface.

2. In a dental articulator a base member having a rearward pair of contoured bearings positioned upwardly and rearwardly of the surface thereof and a forward contoured bearing surface centrally and forwardly thereof, said base surface being adapted to mount a lower dental casting 40 thereon, and a movable upper structure having depending bearing members engageable with the forward and rearward contoured bearing surfaces and an upper dental casting mount intermediate the ends thereof, said contoured 45 bearings having indentations at the lowermost portion of each of the contoured bearings for indicating the centric position of the upper jaw casting with relation to the lower jaw casting whereby movement of the upper movable structure 50 upon said bearing surfaces will simulate the relative movement of the jaws in a dentulous human mouth with the facets of the occlusal surface of the upper and lower teeth operating in natural contact.

55 3. In a dental articulator a supporting structure having a base with a lower cast mount thereon for securing rigidly thereto the cast of a lower jaw, a movable upper structure having an upper cast mount thereon for securing rigidly thereto 60 the cast of an upper jaw, and a three-point suspension between the movable upper structure and the supporting structure comprising two spaced rear suspension members, each having an arcuately movable connection between the upper 65 structure and the supporting structure, and a front suspension member having an arcuately movable connection between the upper structure and the supporting structure said arcuate connection at each of said spaced rear suspension 70 members having a rate of curvature in excess of that of the arcuate connection at the front suspension member.

4. In a dental articulator a supporting structure having a base with a lower cast mount thereon for securing rigidly thereto the cast of a lower

jaw, a movable upper structure overlying said base and having an upper cast mount thereon for securing rigidly thereto the cast of an upper jaw, and a three-point suspension between the movable upper structure and the supporting structure comprising a pair of spaced concave rear bearing members in spaced relation secured to one of said upper structure and supporting structure, a pair of rear pin bearing members adapted to engage respectively the concave bearing members, said pin bearing members being attached to the other of said upper structure and supporting structure, and a front suspension member having a sliding connection including a concave bearing member mounted on the fore of one of said upper structure and supporting structure and a front pin bearing member secured to the other of said upper structure and supporting structure, said forward concave bearing surface having a lesser rate of curvature than that of said pair of rear concave bearing surfaces.

5. In a dental articulator a base member having an upwardly facing surface adapted to mount a lower dental casting thereon, an upper structure relatively movable with respect to said base member, a rearward pair of concave bearings positioned on one of said base member and said upper structure, a rearward pair of bearing pins adapted to engage respectively said rearward pair of the concave bearings, said bearing pins being positioned upon the other of said base member

15

30

and said upper structure, a forward concave bearing secured to one of said base member and upper structure, a bearing pin for slidable engagement therewith secured to the fore of other of said base member and said upper structure, each of said concave bearings having indentations at the most recessed position therein for indicating, in conjunction with said bearing pins, the centric position of the upper jaw casting with relation to the lowering jaw casting, and deviations of the bearing pins from their centric relation with the concave bearings simulating the relative movement of the jaws in a dentulous human mouth with the facets of the occlusal surface of the upper and lower teeth operating in natural contact.

6. The subject matter of claim 5, in which said conjoining bearing surfaces are adjustable in lengthwise relation between the base member and the upper structure, alignment with said indentations serving to establish a parallel relation between the base member and the upper structure as well as defining the centric relation between upper and lower jaw castings.

HAROLD J. THOMPSON.
